UNITED STATES PATENT OFFICE.

JOHN SELLERS BANCROFT AND MAURITZ C. INDAHL, OF PHILADELPHIA, PENNSYLVANIA, ASSIGNORS TO LANSTON MONOTYPE MACHINE COMPANY, OF PHILADELPHIA, PENNSYLVANIA, A CORPORATION OF VIRGINIA.

SHEARING MECHANISM FOR LEAD AND RULE STRIP CASTING MACHINES.

1,193,344.

Specification of Letters Patent.

Patented Aug. 1, 1916.

Application filed September 30, 1915. Serial No. 33,379.

To all whom it may concern:

Be it known that we, JOHN SELLERS BANCROFT and MAURITZ C. INDAHL, citizens of the United States, residing at Philadelphia, 5 in the county of Philadelphia and State of Pennsylvania, have invented certain new and useful Improvements in Shearing Mechanism for Lead and Rule Strip Casting Machines; and we do hereby declare the following to be a full, clear, and exact description of the same, reference being had to the accompanying drawings, forming part of this specification.

The present invention relates to apparatus 15 for producing printers' leads, rules, borders, or printing elements of similar character, and more especially to mechanism adapted to produce the printing elements by an intermittent action, but in indeterminate 20 lengths, the object of the invention being to provide a means whereby the strip may be severed into lengths which may be accurately predetermined, thus adapting the machine for delivering printers' leads or rules, 25 for example, of any desired length within the capacity of the machine, and eliminating the necessity of hand shearing, such as has heretofore been necessary to make the leads and rules fit the forms or make-up for printing.

The invention, while not limited thereto, is primarily adapted for use in connection with Lanston monotype casting machines, such, for example, as that set forth and described in Letters Patent No. 625,998, granted to J. S. Bancroft, May 30, 1899, as modified and adapted for the casting of leads, rules, etc., by intermittent operations of casting and feeding, the machines so modified being now in commercial use and the novel features are set forth in a contemporaneous application for patent, filed in the name of Amos L. Knight, on October 3, 1914, Serial No. 864,894.

45 The invention consists primarily in combining with an intermittently acting lead and rule casting machine for producing a strip of indeterminate length, a shearing mechanism actuated through power connections with the driving mechanism of the casting machine, but controlled by the strip produced thereby in such wise that the shearing mechanism for severing the strip operates when the strip is at rest, thus insur-

ing accuracy in the length delivered with 55 means whereby such length may be varied at will for the production of leads or rules of any desired length, or to fit the work in hand.

The invention further consists in a shearing mechanism in which the cutting device is moved in unison with the strip by a gage interposed in the path of the strip and the cutting operation performed at any point in the length of the strip as determined by the 65 distance between the gage and cutting device.

The invention further consists in certain novel details of construction and combinations and arrangements of parts, all as will 70 be hereinafter described and pointed out particularly in the appended claims.

Referring to the accompanying drawings, Figure 1 is a front elevation of a portion of a Lanston monotype casting machine, many 75 of the parts having no special relation to the present invention being omitted, and parts relating to the present invention added. Fig. 1^a is a view corresponding to Fig. 1 and showing those portions of the 80 machine to the right of the portions shown in Fig. 1, the two views Figs. 1 and 1^a being intended to illustrate in front elevation the machine embodying the present improvements, omitting only the fixed table on which 85 the leads and rules are delivered from the shearing mechanism. Fig. 2 is a sectional elevation looking toward the left in Fig. 1^a and showing the lead and rule guide, the operating mechanism therefor, the lead and 90 rule support, and the movable table, the fixed table being shown in dotted lines. Fig. 3 is a view corresponding to Fig. 2, but omitting the guides and their support and showing, in addition, the cutter operating 95 and lead transferring mechanism. Fig. 4 is a front elevation showing on an enlarged scale portions of the mechanism shown in Fig. 1^a. Fig. 5 is a perspective view showing the cutter operating lever and lever 100 which is carried thereby for operating the guide. Fig. 6 is a perspective view showing the cutter carriage, cutter and adjustable gages for regulating the length of lead or rule to be delivered. Fig. 7 is a sectional 105 plan through a portion of the mechanism shown in Fig. 6, together with the guide roller for supporting the lead or rule strip

at the point where it enters the cutter carriage. Fig. 8 is a detail plan view of the adjustable gage mechanism shown in Fig. 6. Fig. 9 is a sectional elevation substantially 5 in a plane indicated by the line 9—9 in Fig. 1^a, the spring at the left hand end being shown in dotted lines. Fig. 10 is a perspective view of a part of the bell crank lever for operating the cutter. Fig. 11 is a perspective view of the trip mechanism for 10 releasing the interponent to effect the operative connection between the operating or power lever and the bell crank lever.

Like reference characters in the several 15 figures indicate the same parts.

The mechanism illustrated as the preferred embodiment of the present invention is designed for use in connection with a Lanston monotype casting machine and 20 in order that the relationship of the parts may be properly understood from the accompanying drawings, there are shown in Figs. 1 and 1^a in a conventional manner, certain parts of the monotype machine which will be at once recognized by those 25 skilled in the art. The main frame of the machine is indicated by the reference numeral 1; the cam shafts by the numeral 3; the drive shaft by 4; the lever operated by 30 cams on the cam shaft for reciprocating the mold blade, by 5; the bracket which carries the galley by 6; the vertically adjustable melting pot and its supporting bracket by 7 and 8, respectively; and the nozzle 35 through which the molten metal is injected into the mold cavity by the dotted lines at 9.

In the production of printers' leads or rules in the form of a strip of indeterminate length, the molten metal is injected into the 40 mold cavity between the end of the mold blade and the congealed portion of the metal previously injected. This portion of the apparatus, in so far as the specific construction is concerned, is the invention of 45 Amos L. Knight and is embodied in the before-mentioned application. In the present illustration the more or less diagrammatic showing is thought to be sufficient to 50 illustrate the operation of forming and feeding the strip. By reference to Figs. 1 and 1^a it will be seen that the lead or rule indicated at 10 has been formed by the injection of metal through the nozzle 9 and fed forward intermittently by the reciprocation of the mold blade 11 through the medium 55 of the operating lever 5 and connections 12 intermediate said lever and mold blade, a portion of which connections are shown broken away. Metal having been 60 injected through the nozzle 9, congeals, and by the next forward movement of the mold blade 11, it is advanced into a position which will permit of the formation of a cavity for the next increment of metal when 65 the mold blade is withdrawn. Each incre-

ment of metal, fuses with the metal previously injected, thus uniting the lead or rule in the form of a long strip which is intermittently advanced and is guided to the cutting mechanism where it is subdivided into 70 sections of the desired length.

Through mechanism which will be presently described the cutting mechanism is preferably operated in such wise that, when the actual severance is effected, the lead or rule is stationary and the power for operating the cutter is preferably derived from one of the cam shafts 3. Said cam shaft is provided with cam 13 upon which rides an anti-friction roller in the shorter arm of 80 an operating lever 14, pivotally mounted in a bracket at the front of the main frame or stand 1, and with its free end projecting a short distance beyond the melting pot 7.

The cutting or shearing mechanism, except for the parts hereinbefore described is all adapted to be mounted upon or carried by the bracket which supports the melting pot, and is movable in unison therewith into and out of its operative position, and to adapt it for application to the standard monotype machine, it preferably embodies a vertical bracket or frame 15 which is adapted to be secured to the melting pot bracket by bolts 16 or other appropriate fastening means, and at its upper end to support a rigid horizontal bar or extension 17. The entire shearing mechanism *per se* is mounted on the bracket frame 15 and its extension 17; thus the entire mechanism 100 may be readily applied or removed.

Extending down from the part 17 are two supporting arms 18, the lower ends of which carry a horizontal track or way 19 upon which the lower edge of the lead or rule 105 strip may travel. The strip is supported intermediate the mold and the way 19, by a guide roller 20, best seen in Fig. 7 and adapted to be adjusted by a movement of its eccentric support through the medium 110 of a handle 20^a at the front of the frame 15. The shearing or cutting devices are mounted to move parallel with the strip intermediate the guide 20 and the way 19, and said 115 shearing or cutting devices preferably embody a carriage or frame 21 having top and bottom guide surfaces 22 to coöperate with corresponding surfaces formed in the projections 23 of the bracket frame 15. The carriage 21 may conveniently be called a 120 sliding cutter frame, and mounted within it in suitable bearings is a transversely movable knife or cutter 24, said cutter being adapted to intersect the end of the opening 25 through which the strip passes and by 125 the coöperation of the movable cutter 24 and one wall of the opening 25, which is in effect a fixed cutter, the severance of the strip is effected.

In order to locate the cutter with respect 130

to the end of the strip, whereby the accuracy of the length of strip severed may be insured, the sliding cutter frame is provided with a long and preferably square gage rod 26 conveniently guided at its outer end in a guide formed on the extremity of the way 19 and upon this gage rod there is mounted an adjustable gage, with which the end of the lead or rule strip is adapted to contact and whereby the cutting devices will be moved in unison with the strip, for a limited distance. The gage preferably employed embodies a clamp collar 27 adapted to be set in any desired position of adjustment in the length of the rod 26, and a slide 28 having collars 29 embracing the rod 26 with an interposed spring 30 for holding the slide 28 advanced. The slide 28 carries a gage or bracket in position for the end of the lead to contact therewith, and in this preferred construction it carries two of such gages or projections,—that indicated at 31 being pivotally mounted so that it may be turned from the position indicated in full lines to that indicated in dotted lines in Fig. 8, while that at the opposite or outer end of the slide is a rigid gage or projection 32. The pivoted gage or bracket 31 is held in its adjusted position by a retaining collar 33 held advanced by the spring 30 in position for its lateral projections 34 to bear yieldingly against one or the other of the flat surfaces of the gage, thus forming a type of well known retaining devices conveniently adapted for the particular situation where now employed. Obviously, by the use of one or the other of the projections 31, 32, the range of lengths into which the strip may be cut is considerably increased.

40 All of the movable parts of the shearing and cutting mechanism which are moved by and in unison with the lead or rule strip must be made as light as possible, inasmuch as it is frequently desirable to cut exceedingly thin strips, the strength of which would be insufficient to move the cutter if of heavy construction, or, if sufficient to move these parts, the strip itself would be deformed, either at the end or by buckling at an intermediate point. For the reasons stated and others, it is desirable that the cutters be afforded the greatest freedom of movement in unison with the strip, and this has necessitated the provision of means whereby the 55 transversely movable knife may be connected with its operating mechanism without imposing a load on the strip itself. In the preferred construction, a forked operating lever 35 is provided, said lever being pivoted at 60 its upper end on the frame 15 and provided at an intermediate point with a horizontal shaft or pin 36, passing through an eye or bearing 37, Figs. 6 and 7, in the rear end of the knife or cutter 24. The length of the pin 36 between the arms of the lever 35 is sufficient to permit of a full movement of the cutter frame in unison with the strip and a slight overthrow, should the momentum of the parts carry the cutter frame away from the end of the strip. The lower 70 end of the forked lever 35 is normally held in position with the knife or cutter 24 retracted, by a spring 38 and movement is imparted to it for advancing the cutter 24 by a bell crank operating lever 39 having a 75 cam face or wiping surface 40 coöperating with the lower end of the lever 35, the normal position of the two levers being determined by an adjustable stop 41. Movement is imparted to the lever 39 by the long operating lever 14 hereinbefore referred to and the connection between the operating lever 14 and bell crank operating lever 39 is effected by an interponent 42 under the control of the lead or rule strip through the 80 movement imparted by the latter to the gage and sliding cutter frame or carriage. The mechanism for effecting such control embodies a releasing and resetting latch mechanism for the interponent and a lever operated by 85 the sliding cutter frame for operating the latch mechanism, such parts being best seen in Figs. 1^a, 3, 4, 10 and 11. By reference to Fig. 4 it will be seen that a light lever 43 is pivotally mounted on the bracket frame 90 15 at a point intermediate the length of the lever, the upper end of said lever being in position to be moved by the sliding cutter frame 21 whenever the gage is advanced by the lead or rule strip. The lower end of 100 the lever 43 projects between the proximate faces of a pair of escapement pawls 44 and 45, normally held toward each other by an interposed spring 46 and both, together with the lever 43, normally held with the 105 upper end of the lever against the cutter frame 21 by a spring 47, the outer end of which is secured to a downwardly extending fixed arm 48. The lower ends of the escapement pawls 44 and 45 are provided 110 with shoulders 44^a and 45^a, adapted to serve as stop shoulders for the upper end of a bolt 49, the lower end of which bolt is pivotally connected with a bell crank lever 50, mounted on a pin carried by the latch 115 operating bell crank 39. The other arm of the small bell crank lever 50 is adapted to contact with a pin or rod 51, extending through a suitable guide 52 and jointed to the interponent 42, see Figs. 3 and 10. A 120 spring 53 holds the bolt, interponent and bell crank lever 50 toward each other, and a spring 54 connected at its upper end with the frame or bracket 15 normally tends to elevate the bolt 49 and to advance the interponent 42 from the position shown in full lines to the position shown in dotted lines in Fig. 3. The upward movement of the bolt 49 is, however, normally prevented by the escapement pawl 45, against the shoul- 125 130

der 45^a of which the bolt seats, as shown in Fig. 11.

Assuming that the cutter frame 21 is advanced by the end of a lead or rule strip 5 striking the gage or projection 31, the lever 43 will be moved against the tension of spring 47 to swing the escapement pawl 45 away from the end of the bolt 49, with the result that the bolt 49 moves upwardly and 10 the interponent 42 swings out under the operating lever 14. Upon the descent of the operating lever 14, the bell crank lever 39 will be depressed at its outer end, the lever 35 will be swung inwardly, and the 15 knife or cutter 24 advanced to sever the strip. The downward movement of the outer end of the bell crank lever 39 draws the bolt 49 downward and the moment the upper end of the bolt passes the shoulder 20 44^a on the escapement pawl 44, the latter swings inwardly under the influence of the spring 46. Upon the return movement of the operating lever 14 taking place, the bolt is held down and the interponent swung 25 back from the dotted line to the full line position, or to approximately the full line position, for the shoulder 44^a is a very slight distance below the shoulder 45^a and the end of the bolt is transferred from one 30 shoulder to the other, by the return of the sliding cutter frame and lever 43 to normal position under the influence of the spring 47.

From the foregoing it will be seen that the 35 only load imposed upon the lead or rule strip in order to set the cutting mechanism in position to be operated from the power connection, is the inertia of the sliding cutter frame, the lever 43 and escapement pawl 45 with the tension of the spring 47. All 40 of the parts referred to may be made exceedingly light and the tension of the spring adjusted so that it will yield under a very slight pressure, but at the same time the tension of the spring should be sufficient to insure 45 the return of the sliding cutter frame and parts carried thereby to normal position, ready for a subsequent operation and to hold the gage in proper engagement with the end of the strip.

The lead and rule strip after passing 50 through the sliding cutter frame travels along on the guideway 19 and between supporting guides 55 and 55^a, see Figs. 1^a, 2 and 9. These supporting guides are in the 55 form of bars arranged above the guideway 19 and carried on the lower ends of hangers 56 and 56^a depending from a horizontal shaft 57 supported by the arms 18 and forming a journal for the said hangers. The 60 hangers are held toward each other with the supporting guides in proper normal relation by an interposed tension spring 58 and both hangers and guides are held in position over the guideway 19 by spring 59, but are capable 65 of being swung either together or

different distances toward the front of the machine, for example, from the position shown in full lines to that shown in dotted lines in Fig. 2. When so moved, the strip held between the guides 55 and 55^a will be 70 moved transversely off of the guideway 19 and permitted to drop on to the swinging section 60 of the supporting table, as will be hereinafter described. For operating the supporting guides and insuring the 75 proper support of the strip while it is being fed forward and adjusting the cutting mechanism and also for insuring the release of said strip when the supporting guides are swung off to one side by opening 80 the guides and releasing the strip, should there be any tendency for the same to stick, an operating lever 61 is pivotally mounted on the end of the bolt or pin 36 which advances the laterally movable knife or cutter, and this lever 61 is provided with three 85 arms, the lower arm 61^a being adapted to contact with a rocker 62 to be presently described, while the intermediate arm 61^b is adapted to contact with the supporting 90 guide 55^a, and the upper arm 61^c to contact with the hanger 56 of the guiding support 55. The relation of the parts is such that, as the forked lever 35 swings inwardly, the movable knife or cutter is first advanced to 95 sever the strip, whereupon the lower arm 61^a of the lever 61 strikes the rocker 62, whereby its forward movement is arrested and the upper arms of said lever come into contact with the guiding support 55^a and 100 hanger 56 to move said guiding supports laterally. The guiding support 55 is moved a considerably greater distance than the guiding support 55^a, whereby the two are separated so as to permit of the free discharge 105 of the severed section of the strip. To insure the discharge of the strip should there be any tendency of the same to stick against the face of the guiding support 55^a, a series of fingers 63 are secured to the 110 guiding support 55 and extend over and around the guiding support 55^a. They pass through notches or openings 55^b to a point beyond the face of the support when the parts are swung to their extreme left hand 115 position (see Fig. 2). The position of the lever 61 with relation to the operating lever 35 and consequently the normal position of the guiding supports may be determined by an adjustable stop in the upper end of 120 the lever 35, such stop conveniently taking the form of a set screw 64.

The severed section of the lead or rule strip drops down upon a pivoted or swinging section 60 of the receiving table or gallery, and in order to stack the successive sections and move them out of the path of succeeding sections, a rocker 62 is pivotally mounted in bearings in the frame 15 and arm 18, respectively, said rocker being pro- 125 130 135 140 145 150 155 160 165 170 175 180

vided with a series of projections 62^a, which, when the rocker is operated, will oscillate back and forth to the full and dotted line positions shown in Fig. 2. When turned to the full line position, the projections 62^a will push the sections of lead or rule strip forwardly, as indicated in Fig. 9, and when turned back to the dotted line position a space is left for the reception of a succeeding section of strip, one of which latter is shown in dotted lines as descending to the table in Fig. 2, at 65. For operating the rocker 62, it is conveniently provided with a rearwardly projecting arm 66, Fig. 3, connected by a link 67 with the bell crank operating lever 39 at a point forward of the axis of the lever. The link 67, may, if desired, be a yielding link, or embody in its construction a well known form of spring 20 box 68. The downward movement of the forward end of the operating bell crank lever 39 serves to turn the rocker rearwardly to withdraw the projection 62^a from the path of the descending section of strip, and the upward movement of the bell crank lever 39 returns the parts to their normal position and pushes the stack of leads or rules forwardly over the table 60. The pivoted section 60 of the table is hung on the rocker 62 and is provided with a forwardly extended projection 60^a adapted to coöperate with the edge of the fixed section 60^b of the table, and a spring 69 is provided for turning the pivoted section 60 up out of the way when the melting pot is lowered for the purpose of inspection or for other reason during the adjustment of the machine. The pivoted section 60 of the table or galley thus moves with the shearing or cutting mechanism, 40 while a fixed section 60^b remains in position in front of the said mechanism, just as does the galley or table of the ordinary Monotype casting machine.

The operation of the apparatus will be readily appreciated from the foregoing description. The operator having determined the length of the sections of the lead or rule strip he desires, sets the adjustable collar 27 on the rod 26 at the proper point to give the desired distance between the gage or projection 31 and the fixed cutter or coöperating edges of the fixed and movable cutters, and should the length of strip desired be greater than can be secured by the use of the gage 31, the latter is turned out of the way and the gage 32 employed. The strip is advanced intermittently owing to the fact that it is cast in sections, and each section advanced before the next section is cast.

60 The operating mechanism for the operating lever 14 as well as the operating mechanism for the lever 5 which advances the mold blade all derive motion from the same drive shaft, with the result that by properly positioning the cams, the two levers are

caused to move in a proper sequence, the lever 14 moving downwardly at its outer end while the mold blade is being retracted or is at rest, and owing to this relationship it is possible to effect the severance when the strip is stationary. Assuming that the strip has advanced with a jump, causing an overthrow of the sliding cutter frame, the latter will settle back to its correct position for making the cut before the operating lever 70 will move the parts to effect the cut. With the arrangement described it has been found possible to cut the strip into sections which are within the permissible variation from absolute standard in printers' make-up work, 80 and inasmuch as the machine is entirely automatic in its action, it may be set to cast and cut definite lengths and when once set in operation, requires little or no further attention.

85

What is claimed is:

1. In apparatus for producing printers' leads and rules, the combination of the following instrumentalities, to wit: means for alternately casting and feeding successive 90 sections of an integral strip, whereby the strip is at rest during the casting interval, a cutter to which the strip is fed, and means for actuating the cutter to sever the strip during an interval when a cast is being made 95 and the strip is at rest.

2. In apparatus for producing printers' leads and rules, the combination of the following instrumentalities, to wit: means for alternately casting and feeding successive 100 sections of an integral strip, whereby the strip is at rest during the casting interval and the feed movements correspond to the length of the sections cast, a cutter to which the strip is fed movable longitudinally of 105 the strip, means for adjusting the cutter longitudinally of the strip preliminary to the cutting operation, and means for actuating the cutter to sever the strip during an interval when a cast is being made and the 110 strip is at rest.

3. In an apparatus for producing printers' leads and rules, the combination with means for casting successively sections of an integral strip, and means for feeding the strip 115 intermittently distances corresponding to the length of the sections cast and allowing the strip to remain at rest while a cast is being made, of a cutter for severing the strip into sections, means for actuating the cutter while the strip is at rest, and means for adjusting the cutter longitudinally of the strip 120 preliminary to each cutting operation for determining the length of the severed section.

4. In apparatus for producing printers' leads and rules, the combination with means for casting successively sections of an integral strip, and means for feeding the strip intermittently distances corresponding to the length of the sections cast and allowing 130

- the strip to remain at rest while a cast is being made, of a cutter for severing the strip into sections longitudinally of the strip, means for actuating the cutter to sever the strip while at rest, and means for adjusting the cutter longitudinally of the strip during feed movements of the strip.
5. In apparatus for producing printers' leads and rules, the combination with means for casting successively sections of an integral strip, and means for feeding the strip intermittently distances corresponding to the length of the sections cast and allowing the strip to remain at rest while a cast is being made, of a cutter for severing the strip into sections movable longitudinally of the strip, actuating means for the casting, feeding and cutting means, timed to actuate the cutter while the strip is at rest, and means controlled by the advance movement of the strip for adjusting the cutter longitudinally of the strip preliminary to a cutting operation.
10. In apparatus for producing printers' leads and rules, the combination with means for casting successively sections of an integral strip, and means for feeding the strip intermittently distances corresponding to the length of the sections cast and allowing the strip to remain at rest while a cast is being made, of a cutter for severing the strip into sections movable longitudinally of the strip, actuating means for the casting, feeding and cutting means timed to actuate the cutter while the strip is at rest, and means for moving the cutter in unison with the strip a distance corresponding to a portion of the length of a cast section of the strip for positioning the cutter preliminary to the cutting operation.
15. In apparatus for producing printers' leads and rules, the combination with means for casting and feeding a lead or rule strip of indeterminate length, of means for severing the strip into sections of definite length, embodying a cutter movable both lengthwise and transversely of the strip, a gage connected with the cutter and interposed in the path of the end of the strip for advancing the cutter in unison with the strip, an operating mechanism for moving the cutter transversely to sever the strip, and means actuated by the movement of the gage in unison with the strip for controlling the operating mechanism.
20. In apparatus for producing printers' leads and rules, the combination with strip feeding means, of a cutter carriage movable lengthwise of the strip, a gage connected with the carriage and interposed in the path of the end of the strip for moving the carriage in unison with the strip, a transversely movable cutter mounted in the carriage, operating mechanism for the cutter, an interponent in said operating mechanism, and connections intermediate the interponent and carriage, whereby the movement of the carriage controls the setting of the interponent and operation of the cutter.
25. In apparatus for producing printers' leads and rules, the combination with means for casting and feeding a lead or rule strip of indeterminate length, of means for severing the strip into sections of definite length, embodying a bodily movable cutter, a gage connected with the cutter and interposed in the path of the strip for moving the cutter in unison with the strip, an operating mechanism for moving the cutter to sever the strip, and a sliding connection intermediate the cutter and its operating mechanism whereby the strip may be severed at a point determined by the distance between the cutter and gage.
30. In apparatus for producing printers' leads and rules, the combination with means for casting and feeding a lead or rule strip of indeterminate length, of means for severing the strip into sections of definite length, embodying a cutter movable both lengthwise and transversely of the strip, a gage connected with the cutter and interposed in the path of the strip for moving the cutter in unison with the strip, an operating mechanism for moving the cutter transversely to sever the strip, means controlled by the movement of the cutter in unison with the strip for controlling the operating mechanism, and a sliding connection intermediate the cutter and operating mechanism, whereby the strip may be severed at a point determined by the distance between the cutter and gage.
35. In apparatus for producing printers' leads and rules, the combination with means for alternately casting and feeding successive portions of a lead or rule strip of indeterminate length, of means for severing the strip into sections of definite length embodying a cutting device movable for a limited distance in unison with the strip, operating mechanism timed to actuate the cutting device during a casting interval between feed movements of the strip, and means actuated by the movement of the strip to control the operating mechanism.

13. In apparatus for producing printers' leads and rules, the combination with means for casting and feeding a lead or rule strip of indeterminate length, of a cutter carriage 5 movable in unison with the strip, a gage rod movable with the carriage, a gage adjustably mounted on said rod and projecting in the path of the end of the strip, a transversely movable cutter mounted in the carriage, and operating mechanism for advancing the cutter when set by the gage.
14. In apparatus for producing printers' leads and rules, the combination with means for casting and feeding a lead or rule strip 10 of indeterminate length, of means for severing the strips into sections of definite length, embodying a cutter movable transversely of the length of the strip, a gage interposed in the path of the end of the strip to be moved thereby, operating mechanism for the knife embodying an interponent, and means interposed between the interponent and gage embodying a latch moved by the gage, a stop bar connected with the interponent and cooperating with said latch, and a spring for advancing the interponent when released by the movement of the gage.
15. In apparatus for producing printers' leads and rules, the combination with means 15 for casting and feeding a lead or rule strip of indeterminate length, a transversely movable cutter and a gage mounted in the path of and adapted to be moved by the end of the strip, of an operating lever movable in time with the strip feeding mechanism, a 20 knife operating lever, an interponent between said levers, and mechanism controlled by the gage for advancing said interponent to operatively connect the levers.
16. In apparatus for producing printers' leads and rules, the combination with means 25 for casting and feeding a lead or rule strip of indeterminate length, a cutter carriage movable in the direction of the length of the strip, a gage connected with said carriage and interposed in the path of the end of the strip whereby the carriage will be moved by the strip, and a transversely movable cutter mounted in the carriage, of a reciprocal operating lever for the cutter, an 30 interponent in the connection between said lever and cutter, and means for controlling said interponent embodying a spring for advancing the interponent, a stop bar connected with the interponent, a 35 spring pressed latch for holding the bar retracted, and a lever coöperating with the latch and carriage respectively whereby the latch will be released by the movement of the carriage.
17. In mechanism for cutting strips into sections of definite length, the combination with means for feeding the strip, a gage interposed in the path of the end of the strip 40 and movable thereby, and a reciprocal power lever, of a transversely movable knife, a bell crank lever for operating said knife, an interponent between said levers, a stop bar connected with the interponent, a pair of escapement pawls, coöperating with the bar to hold the same retracted, and operating connections intermediate said escapement pawls and gage for releasing the bar when the gage is moved by the strip.
18. An operating and controlling mechanism for the cutter of a strip severing mechanism, embodying a reciprocal power lever, a cutter operating lever, an interponent between said levers, a spring for moving the interponent into its operative position, a catch for holding the interponent retracted against the tension of its spring, a gage interposed in the path of the end of the strip and adapted to be moved thereby, and connections intermediate the gage and catch.
19. A cutter controlling mechanism for strip severing machines, embodying a lever for advancing the cutter, a reciprocal power operating lever, an interponent adapted to connect said levers, a spring for advancing said interponent into its operative position, a stop bar connected with the interponent and movable with the cutter operating lever, a catch for holding said bar retracted, a second catch with which the bar coöperates when the cutter is advanced to retract the interponent, means for shifting said catches in their relation to the bar, a gage controlled by the strip and connections intermediate said gage and catches for releasing the bar and permitting the interponent to move to its operative position.
20. In apparatus for producing printer's leads and rules, the combination with a cutter carriage movable longitudinally of the strip, a transversely movable cutter mounted in said carriage, a gage interposed in the path of the end of the strip and connected with the carriage whereby the latter is moved in unison with the gage, an actuating lever for the cutter, a cutter operating bar carried by the lever, parallel with the path of movement of the carriage, and a bearing on the cutter coöperating with said bar, whereby the cutter may be actuated regardless of the position of the carriage and cutter longitudinally of the strip.
21. In an apparatus for producing printers' leads and rules of definite length from a strip of indeterminate length, the combination with a carriage movable longitudinally of the strip, a gage adjustably connected with said carriage and interposed in the path of the end of the strip, whereby the distance between the gage and carriage may be determined, a cutter mounted to move transversely in the carriage, an actuating lever for the cutter, a cutter actuating bar mounted in the lever in parallelism with the path of movement of the carriage, and a

bearing on the cutter coöperating with said bar, whereby the cutter may be actuated with the carriage in different positions of adjustment as determined by the gage.

5 22. In apparatus for severing a lead or rule strip of indeterminate length into sections of definite length, the combination with means for feeding the strip, a cutter carriage, a transversely movable cutter mounted in said carriage, a gage projecting into the path of movement of the end of the strip, a yielding connection intermediate said gage and carriage, and means actuated by the movement of the gage for controlling 10 the operation of the cutter.

23. In a lead and rule strip cutting mechanism, the combination with strip feeding mechanism and guiding supports between which the strip is fed, of a cutter at 15 one end of the guiding supports, a gage connected with the cutter and interposed in the path of the end of the strip for moving the cutter in unison with the strip, means for moving the cutter transversely to sever 25 the strip, and means for discharging the severed section from between the guiding supports.

24. In a lead and strip cutting mechanism, the combination with strip feeding 30 mechanism, and guiding supports between which the strip is fed, said guiding supports being movable toward and from each other, of a cutter at one end of the guiding supports, a gage connected with the cutter and interposed in the path of the end of the strip for moving 35 the cutter in unison with the strip, means for moving the cutter transversely to sever the strip, means for moving the guiding supports transversely of the guideway, and for simultaneously separating said guiding 40 supports between the guiding supports.

separating the guiding supports, and means for discharging the severed section from 40 between the guiding supports.

25. In a lead and rule strip cutting mechanism, the combination with strip feeding mechanism and parallel guiding supports between which the strip is fed, said guiding 45 supports being movable in unison and toward and from each other, of a cutter at one end of the guiding supports, a gage connected with the cutter and interposed in the path of the end of the strip for moving the 50 cutter in unison with the strip, means for moving the cutter transversely to sever the strip, means for moving the guiding supports transversely in the same direction and simultaneously separating said guiding 55 supports to permit of the discharge of the severed sections.

26. In a lead or rule strip cutting mechanism, the combination with strip feeding mechanism, a guideway along which said 60 strip is fed, parallel guiding supports between which the strip is fed, and a cutter at one end of the guiding supports, of a gage connected with the cutter and interposed in the path of the end of the strip for moving 65 the cutter in unison with the strip, means for moving the cutter transversely to sever the strip, means for moving the guiding supports transversely of the guideway, and for simultaneously separating said guiding 70 supports whereby the severed sections will be discharged from the guideway and from between the guiding supports.
